US00D921364S

(12) **United States Design Patent** (10) **Patent No.:** **US D921,364 S**
(45) **Date of Patent:** **** Jun. 8, 2021**

(54) **BASKET**

(71) Applicant: **CLAIRSON, INC.**, Newark, DE (US)

(72) Inventors: **Milind Sahebrao Nimgulkar**, Pune (IN); **Priya Chaurasia**, Pune (IN)

(73) Assignee: **Clairson, Inc.**, Newark, DE (US)

(**) Term: **15 Years**

(21) Appl. No.: **29/642,797**

(22) Filed: **Apr. 2, 2018**

Related U.S. Application Data

(60) Division of application No. 29/576,492, filed on Sep. 2, 2016, now Pat. No. Des. 814,189, and a continuation-in-part of application No. 15/433,373, filed on Feb. 15, 2017, now abandoned, which is a continuation-in-part of application No. 15/131,323, filed on Apr. 18, 2016, now Pat. No. 9,596,931, said application No. 29/576,492 is a continuation-in-part of application No. 15/131,323, filed on Apr. 18, 2016, now Pat. No. 9,596,931.

(30) **Foreign Application Priority Data**

Mar. 4, 2016 (IN) 201621007648

(51) **LOC (13) Cl.** **03-01**

(52) **U.S. Cl.**

USPC **D3/306**

OTHER PUBLICATIONS

Ex Parte Quayle Action issued in U.S. Appl. No. 29/615,639, dated Jan. 11, 2019 (6 pages), which has the same priority claim as the instant application.

Primary Examiner — Kelley A Donnelly

(74) *Attorney, Agent, or Firm* — Brooks Kushman P.C.

(57) **CLAIM**

The ornamental design for a basket, as shown and described.

DESCRIPTION

FIG. 1 is a perspective view of an embodiment of a basket showing our new design;

FIG. 2 is a front view of the basket shown in FIG. 1;

FIG. 3 is a back view of the basket shown in FIG. 1;

FIG. 4 is a right side view of the basket shown in FIG. 1;

FIG. 5 is a left side view of the basket shown in FIG. 1;

FIG. 6 is a top view of the basket shown in FIG. 1; and,

FIG. 7 is a bottom view of the basket shown in FIG. 1.

1 Claim, 7 Drawing Sheets
